UNITED STATES PATENT OFFICE.

JOHN FLECK, OF LOUISVILLE, KENTUCKY.

LOCOMOTIVE COW-CATCHER.

SPECIFICATION forming part of Letters Patent No. 320,864, dated June 23, 1885.

Application filed February 12, 1885. (No model.)

To all whom it may concern:

Be it known that I, JOHN FLECK, a citizen of the United States, residing at Louisville, in the county of Jefferson and State of Kentucky, 5 have invented certain new and useful Improvements in Locomotive Cow-Catchers; and I do declare the following to be a full, clear, and exact description of the invention, such as will enable others skilled in the art to which it applies to make and use the same, reference being had to the accompanying drawings, and to the letters and figures of reference marked thereon, which form a part of this specification.

15 Figure 1 is a bottom plan view of a portion of a pilot-truck of a locomotive, and Fig. 2 is a front elevation of the same and partial section through the line x x , looking in the direction of the arrows. Fig. 3 is a side elevation of my improvement.

20 My present improvement relates to cow-catchers of locomotives, or devices for removing obstructions which may lie upon a railroad-track.

25 The invention consists of one or more revolving wings or arms mounted upon a horizontal rod, the rotation of which, through mechanism hereinafter described, is calculated to remove obstructions from the track.

30 A represents a portion of the forward frame or pilot-truck of the locomotive.

B is a rod secured to the frame A, and projecting horizontally in front of the locomotive sufficiently far to carry the operating-wings of 35 the obstruction-remover. This rod is mounted in bearings, so that it may revolve under the action of the wings.

C is a cog-wheel mounted upon the rod B, and meshes with another cog-wheel, D, in order to give steadiness of motion.

40 E is a ratchet-wheel mounted upon the same shaft B, and is provided with a spring-pawl, which allows of the shaft B being rotated in one direction only.

45 F is a central bore made in the rearward end of the shaft B, and extends about half-way through the same.

G is a pipe-connection leading from the end of shaft B to either the steam-space of the locomotive or to the exhaust from the steam-

chests of the steam-cylinders. The connection between shaft B and pipe G is made steam-tight, and yet allows of the free revolution of the shaft. The central bore in the shaft terminates at its mid-length in four radial steam-passages, each of which leads to one of the four wings b of the revolving fan H. Each of the wings b has a steam-passage connecting with an opening, a, and leading to the holes c near the outer end of the fan, through which the steam is discharged, and by its reactionary force causes the wings to revolve. The holes c are made at right angles to the length of the wings, and the steam-exhaust takes place in a line tangent to the peripheral path of the wings. 65 The revolution of the wings b and the shaft B carries with it also the wings I and K, which are keyed rigidly to the shaft. The outer series of wings, K, are of less diameter than the others, and are, consequently, higher from the track. The wings I and H are longer, as will be seen in Fig. 1, the latter being from six to nine inches above the track. 70

It will be obvious that by a proper inclination of the revolving series of wings the impact of the atmosphere upon the fans when the train is moving rapidly may be employed to give them the necessary rotation. The wings are adapted by their revolution to throw obstructions from the track. It will also be apparent that the wings or fans might revolve upon the shaft B and the latter remain stationary. 75

Any number of series of fans may be used, and any number of wings in the series. 80

The control or the turning off and on of the steam to the fan is intended to be operated from the locomotive-caboose by means of suitable lever-connections.

The arrangement of the gear-wheels C D is 90 for the purpose of making a connection with the pilot-truck (should it be deemed expedient) and driving the wings by means of the rotation of the wheels.

The inclined wings or vanes may be used in 95 conjunction with the steam-ports in the vanes. The one is the auxiliary of the other, and both can be used upon the same cow-catcher.

This construction or arrangement is often of advantage in instances such as climbing grades, 100

where the full steam-power is necessary to drive the locomotive, or, in the case of exhaust steam, when the locomotive is on a down-grade and the steam shut off.

5. I claim—

1. In a locomotive cow-catcher or device for removing obstructions from the track, a revolving projecting rod, two or more vanes carried thereby, and steam-ports located therein, all constructed to act in combination substantially as set forth.

2. In a locomotive cow-catcher, a horizontally-projecting rod, in combination with two or more vanes having their wings arranged at an inclined angle with respect to said rod, substantially as set forth.

15 3. In a locomotive cow-catcher, a revolving

projecting rod, two or more vanes carried thereby, and a pawl-and-ratchet movement connected with the rod, the whole in combination as set forth.

4. In a locomotive cow-catcher, a projecting rod, in combination with two or more vanes carried thereby, having their wings arranged at an inclined angle with respect to the rod, 25 and provided with steam-ports operatively arranged within the vanes, substantially as set forth.

In testimony whereof I affix my signature in presence of two witnesses.

JOHN FLECK.

Witnesses:

JOHN CHRIST,

JOHN BURKHARDT.
